ROBERT MARCIUS MOSHER, OF DILLON, MONTANA.

PLATEN-ROLLER RELEASE.

1,104,538.

Specification of Letters Patent. Patented July 21, 1914.

Application filed January 31, 1914. Serial No. 614,308.

To all whom it may concern:

Be it known that I, ROBERT MARCIUS MOSHER, a citizen of the United States, residing at Dillon, in the county of Beaverhead and State of Montana, have invented new and useful Improvements in Platen-Roller Releases, of which the following is a specification.

My invention relates to platen roller releases, for use in connection with typewriting machines and analogous structures, my more particular purpose being to provide releasing mechanism, simple in construction and positive in action, for enabling the operator to release the platen roller, or in other words, to render it free of the mechanism ordinarily used for actuating it, thus enabling the platen roller to be turned in either of two directions, independently of the mechanism for actuating it during the general operation of the machine.

Reference is made to the accompanying drawings forming a part of this specification, and in which like letters indicate like parts.

Figure 1 is a horizontal section through the platen roller and parts immediately associated therewith, as used upon a typewriter of the kind manufactured by L. C. Smith & Bros. Typewriter Co., and showing my device as applied thereto. Fig. 2 is a perspective of the lever used for actuating the releasing mechanism. Fig. 3 is an elevation of the barrel carried by the platen roller and forming a part of the releasing mechanism. Fig. 4 is a section through the roller shaft and showing a stop collar mounted upon said shaft. Fig. 5 is a section on the line 5—5 of Fig. 1, looking in the direction of the arrow. Fig. 6 is a fragmentary section, on the line 6—6 of Fig. 5; looking in the direction of the arrow.

Carriage members are shown at 7, 8, and journaled in these members is the platen shaft 9. The platen roller is shown at 10, and may be made of wood, rubber or any other suitable material. This roller is provided adjacent to one of its ends with a cylindrical compartment 10^a, and slidably mounted within this compartment is a barrel 11 made of metal, preferably steel. This barrel is provided at one of its ends with an inwardly extending annular bead 12, and adjacent its other end is provided with an

annular flange 13, which, because of its office, I conveniently designate as a clamping flange. The barrel 11 is further provided with a continuation or neck-like portion 14, and supported upon the latter is an annular bead 15 located externally, as will be understood from Fig. 3. The barrel 11, including the portion 14, the beads 12 and 15 and the clamping flange 13 is made integral, and preferably milled from a suitable casting or solid piece of stock.

An end plate 16, made also of metal, is provided with a portion 17 of reduced diameter, this portion serving to some extent the purpose of a journal neck. The end plate 16 is held in position upon the end of the platen roller 10 by screws 18. Encircling the journal neck 16 and loose relatively to the same is an annular rack 19, toothed externally, and used for turning the platen roller step by step in the usual or any preferred manner.

A stop collar 20 encircles the platen shaft 9, and is secured thereto by a pin 22, which extends through holes 21 for this purpose. Another stop collar 23 is mounted rigidly upon the platen shaft 9. These stop collars prevent longitudinal travel of the platen shaft 9.

A miniature bracket 24 is secured upon the carriage member 8 by a bolt 25, and is provided with a pair of eyes 26. Extending through these eyes is a pin 27, and pivotally mounted upon this pin is a rocking lever 28, which is located between the eyes 26. This rocking lever is provided with a toe 29, which normally engages the annular bead 15.

A lever 30 is provided with a thumb-piece 31, and with a laterally extending portion 32, the latter being provided with an eye 33. A pin 34 extends through this eye and supports the lever 30.

The carriage member 8 is provided with a thickened portion 36, and with cap portions 35 and 37. The carriage member 8 is further provided with a lug 38 located below and in close proximity to the lever 30, and adapted to serve as a limiting stop for the same. The lever 30 carries a lug 39 which is provided with a slanting face 30^a, as may be understood from Fig. 2. Whenever the lever is rocked in a clockwise direction according to Fig. 5, the lug 39^a engages the rocking lever 28 and

causes this lever to rock, so that the toe 29 of the rocking lever, by pressing against the annular bead 15, slides the barrel 11 a little distance in the general direction of 5 the length of the platen shaft to the right according to Fig. 1.

A spiral spring 39 is located within the barrel 11, and presses in opposite directions against the annular bead 12, carried by the 10 barrel, and the collar 20, carried by the platen shaft 9. This spring, by its tension, presses the barrel 11 to the left according to Fig. 1, and thus has a tendency to force the clamping flange 18 against the annular rack 15 19, and also to force this annular rack tightly against the end plate 16 carried by the platen roller. Therefore the tension of the spring 39 normally holds the annular rack 19 rigid relatively to the platen roller. 20 When, however, the lever 30 is turned by hand in a clock-wise direction according to Fig. 5, or in other words the operator using the machine presses the thumb-piece 31 away from her, the spring 39 is compressed 25 slightly, the barrel 11 is moved a trifle in the general direction of its own length, and the annular rack 19 is disengaged from the platen roller, yet is not materially disturbed as to its general position.

30 The operation of my device is as follows: The parts being assembled and arranged, as above described, the platen roller and annular rack 19 are normally actuated as usual or customary in this art. If, however, the 35 operator desires to turn the platen roller backward to any desired extent, or to turn it forward to an extent less than it generally moves in rotating a single step of its travel, the operator merely places her thumb 40 upon the thumb-piece 31 and presses the same as above described. The lever 30 being thus swung upon its mounting, the lug 30^a actuates the rocking lever 28 and virtually locks the same in the position which 45 it thus assumes. In doing this, the spring 39 is practically locked under compression so that the annular ratchet 19 remains free, even after the operator removes her thumb from the thumb-piece 31. The movable 50 parts associated with the platen roller remain in the respective positions into which they are thus brought, and are only restored to their respective normal positions by a reverse movement of the lever 30. The 55 mechanism above described, enables the typewriting paper to be so shifted that the writing may be placed anywhere upon it, independently of the spacing ordinarily done by the machine, and also enables the 60 same sheet of paper to have typewritten characters placed upon it regardless of the positions of other typewritten characters placed upon it before. Again, the wear of the movable types upon the platen roller is 65 distributed to much better advantage, be-

cause, in using my device, the type letters do not strike repeatedly in the same position upon the platen roller.

I do not limit myself to the precise construction shown, as variations may be made therein without departing from the spirit of my invention. Neither do I limit my apparatus to use upon a particular type of machine, as the construction may be varied to adapt it for service upon typewriting 75 machines of various kinds, and upon mechanism other than typewriting machines.

Having thus described my invention, what I claim as new and desire to secure by Letters Patent is as follows:

1. In a platen roller release, the combination of a platen roller, an annular ratchet for turning the same, said ratchet being normally loose relatively to said platen roller, a barrel carried by said platen roller and 85 provided with a clamping flange for engaging said annular ratchet, and forcing the latter into operative engagement with said platen roller, a rocking lever engaging said barrel, and an actuating lever provided with a lug for engaging said rocking lever in order to shift the position of said rocking lever.

2. In a platen roller release, the combination of a platen roller provided adjacent to one of its ends with a compartment, a barrel extending into said compartment and loose relatively to said platen roller, a spring located within said barrel, for the purpose of moving said barrel relatively to said roller, a clamping flange carried by said barrel and having a general annular form, an annular ratchet loosely encircling said barrel and located between said annular flange and said platen roller, for the purpose of 100 turning said platen roller, an annular bead carried by said barrel, a rocking lever engaging said annular bead, and an actuating lever movable by hand and provided with a lug for engaging said rocking lever.

3. In a platen roller release, the combination of a platen roller, a rack for turning the same, a barrel carried by said platen roller and movable relatively thereto, a spring for shifting said platen roller relatively to said barrel, a clamping flange carried by said barrel and adapted, upon movements of said barrel, to press said ratchet against said platen roller, a rocking lever in operative engagement with said barrel for the purpose of shifting said barrel relatively to said roller in order to disconnect said rack from said platen roller, and means controllable at the will of the operator for locking said rocking lever in a number of 115 predetermined relative positions.

4. A device of the character described, comprising carriage members, a shaft mounted thereupon, a platen roller mounted upon said shaft and provided with a sub- 120

stantially cylindrical compartment, an end plate mounted upon said platen roller and disposed adjacent said compartment, said end plate being provided with a journal neck, an annular rack engaging said end plate and encircling said journal neck for the purpose of turning said roller when clamped against said end plate, a barrel extending into said compartment and provided with a clamping flange for engaging said annular rack, a rocking lever for engaging said barrel and drawing the same slightly out of said compartment, means for normally holding said barrel at the limit of its travel within said compartment, a rocking lever engaging said barrel for the purpose of drawing it slightly outward from said barrel and thereby compressing said spring, and mechanism controllable at the will of the operator for locking said rocking lever in a number of predetermined positions.

5. A device of the character described, comprising a platen roller, an annular ratchet disposed adjacent one end of said roller and adapted to turn said roller by frictional engagement therewith, a clamping flange for pressing said annular ratchet toward said roller and thereby enabling said 25 ratchet to turn said roller, means including a rocking lever for shifting said flange relatively to said annular rack, and an actuating lever disposed adjacent said rocking lever and provided with a lug for engaging said 30 rocking lever, said lug having a slanting face, said actuating lever being under control at the will of the operator.

6. In a platen roller release, the combination of a platen roller, an annular ratchet 40 for turning the platen roller and adapted to engage one end of the latter, a barrel carried by the platen roller and movable relative thereto, the barrel having a clamping flange for engaging the annular ratchet, a 45 spring acting on said barrel and tending to

force the clamping flange against the annular ratchet and the latter against the said end of the platen roller, and means for moving the barrel against the tension of the spring to disengage the clamping flange 50 from the annular ratchet and free the latter from clamping engagement with the platen roller.

7. In a platen roller release, the combination of a platen roller provided with an end plate, an annular ratchet engaging said end plate and adapted to turn the platen roller, a barrel carried by said platen roller and movable relative thereto, the barrel being provided with a clamping flange for engaging 55 the annular ratchet, a spring for moving said barrel in one direction and tending to force the clamping flange against the annular ratchet and also to force the ratchet against the end plate of the platen roller, 60 a rocking lever engaging said barrel, and an actuating lever provided with a lug for engaging the rocking lever to shift the position of said rocking lever.

8. A device of the character described, 70 comprising a platen roller provided with a compartment in one end, an end plate on said end of the platen roller and having a journal neck, an annular ratchet engaging said end plate and mounted loosely on the 75 journal neck, a barrel extending through the end plate and into the said compartment, and provided with a clamping flange for engaging said annular ratchet, a spring for pressing said barrel inward in the compartment 80 to cause the clamping flange to press the annular ratchet against the said end plate, and a lever mechanism for moving the said barrel slightly outward to free the annular ratchet from operative engagement 85 with the end plate of the platen roller.
